UNITED STATES PATENT OFFICE.

OTTO KERSCHT, OF DETROIT, MICHIGAN.

INTERNAL-COMBUSTION ENGINE.

1,119,432.

Specification of Letters Patent.

Patented Dec. 1, 1914.

Application filed March 10, 1914. Serial No. 823,678.

To all whom it may concern:

Be it known that I, OTTO KERSCHT, a citizen of the United States of America, residing at Detroit, in the county of Wayne and State of Michigan, have invented certain new and useful Improvements in Internal-Combustion Engines, of which the following is a specification, reference being had therein to the accompanying drawings.

10 The invention relates to internal combustion engines of the semit-Diesel type, and it is one of the objects of the invention to utilize the heat of combustion for pre-heating the air which is subsequently compressed 15 to produce automatic ignition.

In the drawings: Figure 1 is a vertical longitudinal section through the engine; Fig. 2 is a section on line $x-x$ Fig. 1; Fig. 3 is a section on line $y-y$; and Fig. 4 is a 20 section on line $z-z$.

A is the engine casing which is formed with the cylinder chamber B containing the piston C, and a cylindrical valve chamber D having its axis parallel to the axis of the cylinder and piston. E is a pump piston within the cylindrical chamber D, and F and G are pitman or piston rods connecting the pistons C and E with the crank-shaft H.

To utilize the heat of combustion in pre-heating the air, the walls of the engine casting are hollow and are provided with a plurality of passages as follows: In the wall surrounding the lower part of the cylinder B is a passage I having an inlet port I' near its lower end, and after passing part way around the cylinder communicating with a port I'' . This port is so located that when the piston C is at the upper end of its stroke a port C' therein will register with the port I'' for the admission of air from the passage I into the crank case chamber. The piston C has formed in its head a passage J having the inlet ports J' in its bottom wall and an outlet port J'' in its peripheral wall, which is adapted, when the piston is at the lower end of its stroke, to register with a port K communicating with the passage K' in the inner wall of the cylinder, or between the power cylinder B and the valve cylinder D. This passage K' extends upward and communicates through a port K'' with an annular passage L extending about the upper part of the cylinder B, or that portion which is vacated by the piston when at the downward end of its stroke. This passage L is separated from the passage I by a division

strip L', and upon the opposite side of the cylinder communicates through a port L'' with the passage M, this being parallel to the passage K and separated therefrom by the division strip M'. The passage M extends downward to the lower end of the cylinder and there communicates through a port M'' with the cylinder D when the piston E in said cylinder is at the upper end of its stroke, said port being covered by the piston during its downward stroke. The piston E is provided with a port N, which, when at the downward end of its stroke, registers with the port connecting with the passage N', which extends up to the upper end of the cylinder and communicates by a lateral passage N'' with an annular chamber N''' in the head of the cylinder. This chamber communicates by ports O with a valve chamber O' containing a check valve P, which is held to its seat by a spring P'. The arrangement of parts just described is such that during the operation of the engine, air is first drawn in through the passage I and through the ports I'' and C' when in registration, into the crank case chamber, the suction produced by the up-stroke of the piston causing the movement. Upon the down-stroke of the piston the air within the crank case is compressed, and when the ports J'' and K register, this compressed air is forced first through the passage J' in the piston and then through said registering ports into the passage K' and 80 through the port K'' into the passage L. After passing around the cylinder in this passage L the air passes through the port L'' and downward through the passage M to the port M'', which, when uncovered by 85 the piston E, admits the air into the lower part of the cylinder D. Upon the down-stroke of the piston E the air in said cylinder is further compressed, and when the port N registers with the passage N' this 90 compressed air is premitted to pass through said passage N', lateral passage N'' and annular passage N''' to the ports O and valve case O', opening the valve P against the tension of the spring P' and entering the 100 cylinder B. This occurs when the piston C is at the downward end of its stroke, and upon the return stroke of this piston the air contained within the cylinder is further compressed until it reaches a temperature 110 suitable for ignition.

The oil or other liquid fuel which is used

in the engine, first enters a passage Q in the wall of the cylinder D, and after passing downward enters through a port Q' into said cylinder above the piston E. This 5 piston is provided centrally with a plunger E' engaging a bore in a head R fixed within the cylinder D, and above this head R is a piston valve S sliding in the cylinder D. This valve S has a port S' at one side thereof, which is adapted to register with a port T leading into the main cylinder B. There is also a second head U fixed in the cylinder D above the piston valve S and forming a clearance chamber U' thereabove. 10

15 In operation the retraction of the piston E will pump oil or other liquid fuel into the cylinder D, forcing it upward against the valve S until the latter registers its port S' with the port T. The valve S in its downward direction is moved by the suction created on the lower side thereof. The displacement of the plunger E' during the upward stroke of the piston E will then force the desired quantity of oil through 20 the port T into the cylinder B. This occurs during the time in which the piston C is on its power stroke and the heat due to the high compression of the air will cause automatic ignition of the fuel which will be 25 burned during said power stroke, combustion being supported by the air returning from the chamber U' through the port U².

30 By means of the construction above described, the air which is used to support combustion is gradually heated by being passed successively from the cooler to the hotter parts of the walls of the engine casting, and is then further compressed by the piston E and delivered into the cylinder 35 B. Here the upward stroke of the piston C gives the final compression which produces the automatic ignition of the oil entering through the port T. Thus I utilize the heat of combustion which would be 40 otherwise wasted, in raising the temperature of the air before its final compression. The valve P is preferably mounted in a casing V which is removably secured in the cylinder head, and thus whenever it is necessary 45 to re-seat this valve it may be easily detached for this purpose. To further utilize the waste heat of the engine the exhaust conduit is formed in the hollow wall and extends around the lower end of the 50 pump cylinder before escaping to the external atmosphere. As shown W is the exhaust port in the engine cylinder which is uncovered by the piston when at the lower end of its stroke. W' is a conduit leading 55 downward from the port W within the hollow walls, and W² is a laterally-extending conduit which passes about the pump cylinder to the port W³. This permits the heat from the combustion gases to be communicated to the cylinder walls and to the air 60

passages therein. I also preferably provide means for scavenging the cylinder from burnt gases, comprising a port X in the cylinder connected by a passage X' with the port X² in the crank-case chamber. 70 This permits a small portion of the compressed air in the crank-case to pass up to the port X when the latter is uncovered by the piston, and the air thus admitted sweeps around a deflector X³ and drives the remnant of burnt gases out through the exhaust port W. 75

What I claim as my invention is;—

1. An internal combustion engine, comprising power and pump cylinders having 80 hollow walls forming independent air and fuel passages, pistons in said cylinders co-operating with ports therein for progressively forcing air through said passages from the cooler to the hotter portions of 85 said walls and finally forcing the air into the power cylinder, and means actuated by the pump piston for also forcing the fuel into said power cylinder.

2. An internal combustion engine, comprising power and pump cylinders having 90 hollow walls forming air and fuel passages, a piston in said power cylinder co-operating with ports therein for forcing air through said hollow walls progressively from the 95 cooler to the hotter portions thereof, and a piston in said pump cylinder for forcing the heated air into the power cylinder during the compression stroke of the power piston and for forcing the fuel into said power cylinder during the power stroke of the piston. 100

3. An internal combustion engine, comprising power and pump cylinders having hollow walls forming air and fuel passages, a piston in said power cylinder co-operating 105 with ports therein for forcing air through said hollow wall from the cooler to the hotter portions thereof, a piston in said pump cylinder for forcing the heated air into said power cylinder during the compression 110 stroke and for forcing the fuel into said power cylinder during the power stroke, and a chamber into which the air from said power cylinder is ejected during the compression stroke and from which it returns to 115 commingle with the fuel during the power stroke.

4. An internal combustion engine, comprising power and pump cylinders provided with hollow walls forming air and fuel passages independent of each other, a piston in said power cylinder co-operating with ports therein for forcing air through said hollow walls from the cooler to the hotter portions thereof, and a double acting piston in said 120 pump cylinder operating on one side thereof to force the heated air into said power cylinder and operating on the opposite side thereof to force the fuel into said cylinder. 125

5. An internal combustion engine, com- 130

- prising power and pump cylinders having hollow walls forming air and fuel passages, a piston in said power cylinder coöperating with ports therein for forcing air through 5 said hollow walls from the cooler to the hotter portions thereof, a double acting piston in said pump cylinder operating on one side thereof to force the heated air into said power cylinder and operating on the opposite side to force the fuel into said cylinder, and a valve in said pump cylinder operated by said piston and controlling the admission of fuel into the power cylinder. 10
6. An internal combustion engine, comprising power and pump cylinders provided with hollow walls forming air and fuel passages, a divided crank case having the chambers thereof respectively communicating with said power and pump cylinders, a piston 15 in said power cylinder coöperating with ports therein and with said crank case chamber for forcing air through said hollow walls from the cooler to the hotter portions thereof, a double acting piston in said pump cylinder operating on one side thereof in conjunction with the connecting chamber of the 20 crank case for forcing the heated air into said power cylinder and operating upon the 25
- opposite side to propel the fuel into said cylinder, a chamber into which the air compressed in said power cylinder during the compression stroke is forced and from which it returns during the power stroke and a valve for controlling the admission of fuel into said power cylinder during the power stroke to commingle the same with said returning air to effect combustion. 30
7. An internal combustion engine, comprising power and pump cylinders provided with hollow walls forming air and fuel passages, a piston in said power cylinder coöperating with ports therein for forcing air through said hollow walls from the cooler to the hotter portions thereof, a piston valve, and a double acting piston in said pump cylinder operating on one side thereof to force the heated air into said power cylinder, and operating on the opposite side thereof to force the fuel into said piston valve. 35

In testimony whereof I affix my signature 40 in presence of two witnesses.
